LANTZ & RUSSELL.

Grain Cleaner.

No. 21,139.

Patented Aug. 10, 1858.

UNITED STATES PATENT OFFICE.

J. LANTZ AND J. RUSSELL, OF WHEELING, VIRGINIA.

IMPROVEMENT IN MACHINES FOR CLEANING WHEAT.

Specification forming part of Letters Patent No. 21,139, dated August 10, 1858.

To all whom it may concern.

Be it known that we, JESSE LANTZ and JOHN RUSSELL, of the city of Wheeling and county of Ohio, in the State of Virginia, have invented a new and Improved Wheat-Cleaner and Smut-Machine, which we denominate the "Double-Acting Suction Wheat-Cleaner," and "Double-Acting Centrifugal Wheat-Rubber;" and we do hereby declare that the following is a full and exact description of the same as nearly as practicable to be described.

This invention differs from all other smut-machines or wheat-cleansers in many instances, and is calculated to clean or cleanse wheat of all articles of filth, or substances which should not be ground with the wheat for bread, and at the same time to save the defective grains of wheat and cheat in a clean state for horse-food, by separating this article from the dust and cockle by a process differing from all other inventions designed for this purpose, and is correctly demonstrated by the diagrams and drawings as referred to in the following explanation. The wheat is first passed through a small screen constructed with two riddles, as represented on Figure 3, and marked H, the upper riddle, (marked M,) being so calculated as to let the wheat pass through with ease, while all articles of greater dimensions than wheat-grains are passed off at the spout L, the wheat and all smaller articles falling through upon the lower riddle, (marked N,) this riddle being so constructed as to let all articles through smaller than grains of wheat—such as cockle and small gravel—which fall upon the incline floor or plane, (marked i,) and by the shaking of the screen by the eccentric or cam, (marked R,) striking against the stay, (marked S,) and thrown back by the spring, as seen at U, coming against the stay (marked t) in quick motion, the cockle and small gravel are thrown off at the spout T. The wheat, so riddled of much filth, then passes into the hopper G, (best seen at Fig. 1, which exhibits the front view of this invention.) This operation is performed by a band around two pulleys—one on the main shaft of the machine, as seen at g, Fig. 3, the other on the axes of the cam, as seen at f, Fig. 3, end view of the invention. After this first process, the wheat being so riddled, it falls into the hopper G and enters the arch F through an opening about six inches above the end of the arch F and immediately over

the hopper, (marked V,) as seen in Fig. 1. The wheat on entering this opening in this arch is again filtered by an atmospheric process called "suction," which is created by the power of the fan drawing the atmosphere through the arch F, immediately over the hopper V. At this point the wheat falls into the hopper V and enters the smut machine or cylinder, (marked Z,) as seen at Figs. 1 and 2, and a large amount of the smut-balls, cheat, and other filthy substances are drawn over the arch F by the current of atmosphere created by the fan to the point marked J, where another separation takes place, the smut-balls and dust passing into the fan-box D immediately opposite the point marked J through an opening, (marked C,) as represented by black lines drawn over the diagram, which represents the materials of the machine, (marked A.) At this point the defective grains of wheat and cheat that are heavier than the smut-balls and other substance that may have been drawn over fall out at the valve J in a clean state to be ground as horse-food. This is the first and most important operation of cleansing the wheat, as the greater portion of the smut-balls are here blown out by the fan at the point marked Q, as represented on Fig. 2, back view of the invention, and never enter the smut-machine to be broken into a black dust with the wheat as it passes through the rubbing process to create a darkness upon the surface of the wheat-grains. This, therefore, is quite important to prevent a darkness in the flour, which originates from the smut-balls and dark substances being broken too largely in all other smut-machines with the wheat. By this process the greater portion is carried off without entering the smut-machine. The wheat, together with all the impure articles that may not have been carried out by this first operation, falls into the hopper V, as before described, and enters the smut machine or cylinders near the axes of the machine upon the horizontal wheel W, upon which is set or fixed many vertical pins from two to six inches long, through which the wheat in this state is thrown by the centrifugal force as it revolves, striking against these pins and breaking to pieces the smut-balls and all other impure articles that may have been left by the first operation, or nearly so, into dust, and this striking against the side of the internal cylinder-case, which

is perforated immediately opposite with holes, as seen in Fig. 2, (marked z .) through which the dust so made passes into the chamber between the external and internal cylinder-cases, as seen in Figs. 1 and 2, (marked e .) from whence the dust is eradicated by the fan through the spout marked y , Figs. 1 and 2, into the fan-box D, and blown out at the spout marked Q, as seen on Fig. 2, back view of the machine. The wheat next falls into a circular hopper attached to the internal cylinder-case, as represented by the lines marked P, and extending under the wheel W, with the mouth or opening around the main axis at x . The wheat and all articles of filth that may not have been carried off by this operation fall through upon the wheel X, which is constructed in the same manner as the wheel W, and undergoes the same operation as before by the revolution of this wheel also, which breaks to pieces the smut-balls and other impure articles that may not have been destroyed by the last operation to a still greater extent as it passes through the pins upon this wheel by the centrifugal force to the extremity, at which point the wheat in this state, with all articles of filth—such as rat-dung and mice-dung—too hard to have been broken as it passed through the pins upon the wheel X, falls out upon an adjustable reeded rubber, (marked o .) which sits at the base of the internal cylinder-case, and so constructed that it can be raised or lowered by set-screws. The wheat in this state is passed between this and another rubber connected to the wheel X, forming a flange all round the bottom like a dished hoop, as seen at i , coming near the adjustable rubber, and by the powerful revolution of this flange-rubber against the reeded rubber every article of filthy substance is broken into dust and thrown round to the spout I with the wheat, and enters the arch E at the point marked K. At the point K in the arch E a final cleansing operation takes place, the wheat falling

out at the spout of the arch, below the point K, as seen at v , and the dust, faulty grains of wheat, and cheat carried over the arch E to the point marked J by the power of atmospheric suction created by the fan, as before stated, in the arch F, where a last separation takes place, the dust passing into the fan-box D, and, as in the first operation, it is blown out at the spout Q, (seen on Fig. 2,) while all faulty grains of wheat and cheat that may have come to this point fall out through the valve marked J, as before shown and described of the arch F.

The adjustable reeded rubber is best represented by Fig. 7, in connection with Fig. 1, at the lines marked o and w . The line marked o is the reeded rubber, represented to sit at the base of the internal cylinder-case, as seen in Fig. 7, and may be raised or lowered by set-screws under the frame, above the fan-box, as seen at r , Figs. 1 and 2, which gives the name "adjustable." This reeded rubber can be raised at pleasure to any space for the wheat to pass between that and the flange-rubber, as the case may require, for complete destruction of all impure articles of filth to which wheat is subject by long standing in mills and other places of deposit by rats and other animals.

What we claim as our improvement in this invention is—

1. The additional air tube or arch F, in connection with the air tube or arch E, for the purpose of receiving the wheat through an aperture in pipe F, above the hopper V, and from the hopper G, as described.

2. The adjustable reeded rubber o ; combined with the flange-rubber i , constructed and operating as and for the purposes described.

JESSE LANTZ.
JOHN RUSSELL.
